UNITED STATES PATENT OFFICE.

FRED S. PEARSON, OF BOSTON, MASSACHUSETTS.

SWITCH FOR RAILWAYS.

SPECIFICATION forming part of Letters Patent No. 664,579, dated December 25, 1900.

Application filed March 14, 1899. Serial No. 708,994. (No model.)

To all whom it may concern:

Be it known that I, FRED S. PEARSON, a citizen of the United States of America, and a resident of Boston, county of Suffolk, State 5 of Massachusetts, have invented certain new and useful Improvements in Switches for Railways, of which the following is a specification.

This invention is an improvement in automatic switches for street-railways, and has 10 special reference to switches for use on railways over which motor-cars are run or cars propelled by other means than horses; and this improvement has for its object a switch that can be operated or controlled wholly by 15 the car passing over the road.

In the accompanying drawings, illustrating my improvement, Figure 1 is a top view, partly in section, of a section of the road containing the improvement, showing the switch-tongue 20 and switch mechanism. Fig. 2 is a transverse section of the same through the plane indicated by the line $x-x$, Fig. 1. Fig. 3 is a detail showing a vertical section at $y-y$, Fig. 1. Fig. 4 is an enlarged vertical section of 25 the road through the plane indicated by the line $z-z$, Fig. 1, showing the switch-operating mechanism in a position midway between its two extreme positions and the wheel of the car depressing the actuator in the rail. Figs. 30 5 and 6 are similar views showing, respectively, the switch-operating mechanism in its extreme opposite positions when the switch is open and closed; and Fig. 7 is a detail.

In this improvement the switch is thrown 35 from one position to the other or opened or closed, as desired, by the wheel of the car passing over the car-rail and without stopping the car or in any way affecting its running.

40 The switch-operating mechanism is located in a pit or excavation beneath the road-bed and is moved or operated by an actuator situated in the car-rail and depressed by the car-wheel as the latter passes along the track. 45 In the construction shown in the drawings this actuator consists of a lever A, pivoted at one end in an elongated opening in the rail in such manner that the other or free end can be raised above the surface of the 50 rail in position to be depressed by the car-wheel passing over it. From the free or movable end a of the lever depends a post B,

which extends vertically into the pit and is moved up and down therein as the lever is raised and depressed. This post is pivoted 55 to the lever in order that it may maintain a vertical position as it moves and is further held in this position and kept from swinging by a socket in the platform B' on the bottom of the pit, in which the end of the post fits 60 and moves.

On opposite sides of the post B in the pit are two arms E F, mounted on suitable shafts or bearings C and D, so as to extend toward each other and move up and down in a vertical plane. On the same shafts C and D are other arms G and H, respectively, extending downward and in a direction substantially at right angles to the arms E and F. The ends of these arms G and H are connected by the link 70 or tie-rod I, whereby these arms, and hence the arms E and F, mounted on their respective shafts, are caused to move together. The arms E and F are thus connected with one another and, as will be seen by reference to 75 Figs. 4, 5, and 6, always move in opposite directions. As one arm E swings upward the other arm F will swing downward, and vice versa. On the shaft C is mounted a third arm K in such position as to swing back and forth as 80 the shaft turns. To the end of this arm K is connected the rocking rod L, the other end of which is attached to the switch-tongue, and hence as the arm K swings back and forth with the shaft it turns the switch-tongue 85 in opposite directions to open and close the switch. By reference to Figs. 5 and 6 it will be seen that as the arm E turns downward it swings the arm K so as to turn the switch in one direction, and as the arm F turns downward it swings the arm K in position to reverse the switch or turn it in the other direction. The downward movement of the arms E and F thus swings the arm K in opposite directions and reverses the position of the 90 switch or opens and closes the latter. The arms E and F are turned downward to thus operate the switch by engagement with the sliding post B in the following manner: On the ends of these arms E and F, respectively, 95 are loosely mounted pawls M and N, so constructed and pivoted to their respective arms that when free to turn their upper ends will swing inward and rest against the sides of

the post B. The bottoms of these pawls are formed with the projections *m* and *n*, so constructed as to come in contact with and rest upon the platform B' when the arms E and F 5 swing downward. As will be seen from the drawings, as these projections strike against the platform the upper ends of the pawls are thrown outward and away from the post B.

On the sides of the post B against which 10 the pawls rest are shoulders or projections *e* and *f*, so placed that when the post is in its upward position—that is, when it has been lifted up by the actuator—the shoulder will be immediately above the end of the upper- 15 most pawl or the pawl on that arm, E or F, which is turned upward, as is shown in Fig. 4 and as will be understood from Figs. 5 and 6. If now when the pawl and shoulder are thus 20 engaged the post is pushed down, the shoulder pressing on the end of the pawl will turn the arm E or F connected with it downward, and thus swing the arm K in either direction, as it may be, to reverse the switch. As the 25 arms E and F are connected together, one of them will be raised as the other is turned down, and to prevent the pawl of the upward-moving arm, which is thus freed from contact with the platform, from swinging inward and engaging with the shoulder on the post, and 30 thereby interfering with the movement of the arms and the operation of the mechanism, the pawl is held away from the side of the post as it moves up by the latches O and P. These 35 latches are mounted on the standard Q, Fig. 7, erected on the platform B, in position to engage with the ends of the pawls. The latches are pivoted to the standard so they can swing outward, but are prevented from swinging inward toward each other by the studs *q q*. On 40 the ends of the pawls are pins *m'* and *n'*, and on the ends of the latches are cam-shaped projections *o* and *p*, arranged to engage with the pins, whereby the pawl in its upward movement is held out away from the side of 45 the post until its engagement with the latter is required.

The operation of the above mechanism is as follows: In Fig. 6 the parts of the mechanism are shown in their respective positions 50 when the switch is open and the actuator down. As will be seen, the arm E is raised, with the end of its pawl M lifted above the end of the latch O and resting on the side of the shoulder *e* on the post B, while the arm F is turned down with the projection *n* of its pawl N resting on the platform B' and the upper end of the pawl thrown outward away from contact with the side of the post. If now it is desired to reverse the switch, the actuator 55 A is raised, as indicated by dotted lines, and the post B drawn up. As will be understood from Fig. 6 and as is shown in Fig. 4, the end of the pawl M will now drop below the shoulder *e* in position to engage with the latter, 60 and as the actuator is depressed by the car-wheel, as shown, and the post B thus pushed down the shoulder will press against the end.

of the pawl as the post descends and swing the arm E downward, the pin *m'* on the pawl passing back of the cam projection *o* on the latch O. As the arm E swings downward it turns the shaft C and swings the arm K, mounted on the latter, to one side in position to slide the rocking rod L and reverse the switch-tongue and close the switch. The arm 75 E continues to descend with the post until the projection *m* on the bottom of the pawl M strikes against the platform B', when the upper end of the pawl will be thrown out away from the side of the post and from engagement with the shoulder *e*, as in Fig. 5, the pin *m'* having passed below the cam projection *o* on the latch. Since the arms E and F are connected together by the arms G and H and rod I, as the arm E is thus pushed 80 downward by the descent of the post the opposite arm F will be swung upward and its pawl N lifted from the platform B' and be free to turn. By referring to Figs. 4 and 6 it will be seen that as the pawl N moves upward 85 with the arm F the pin *n'* on the end of the pawl slides along the outside of the cam projection *p* on the latch P and holds the pawl from swinging inward and coming under the shoulder *f* on this side of the post and interfering with the descent of the latter. The 90 pin continues to move along the projection on the latch and keeps the pawl out of engagement with the shoulder as the pawl is raised until the end of the pawl is above the 95 bottom of the shoulder and is in its upward position resting on the side of the shoulder *f*, as in Fig. 5. The post is now all the way down, the wheel having passed over the actuator, and the parts of the mechanism in the 100 position shown in Fig. 5, with the switch reversed or closed. As seen, the arm E is now 105 down, with the bottom *m* of its pawl M resting on the platform B' and the upper end of the pawl thrown back from the post and out 110 of engagement with the shoulder *e*, and the arm F raised, with its pawl N resting against the side of the post in position to drop under and engage with the shoulder *f* when the post 115 is raised. To reverse the switch again, the 120 actuator is raised and the post B lifted up, as before. The pawl N now comes under and engages with the shoulder *f* and as the post descends swings the arm F downward and turns the shaft D. This shaft in turning by 125 means of the arm H, rod I, and arm G on the shaft C turns the latter shaft and swings the arm K back in position, as shown in Fig. 6, to slide the rod L so as to reverse or open the switch. As before, when the one arm F 130 swings down the other arm is turned upward and the pawl M raised, the pin *m'* on its upper end sliding along the outside of the cam projection *o* on the latch O and keeping the pawl from engagement with the shoulder *e*, as was the case with the pawl N on the arm F. The parts of the mechanism are thus brought back into the position shown in Fig. 6, ready to reverse the switch to a closed po-

sition. It will thus be seen that every time the post B is made to descend it engages with one or the other of the arms E or F, according as to whether the switch is already open or closed and the one or the other arm is raised, and turning this arm downward swings the arm K in position to reverse the switch, and hence to change the switch from an open to a closed or a closed to an open position it is only necessary to raise the post B by lifting the actuator and then push the post down by depressing the actuator by the car-wheel, when the switch will be reversed.

The engagement of the rocking rod L with the switch is shown in Figs. 1 and 3. The rocking rod, as shown, moves in a tube or casing L' and is connected at its farther end to an arm l, mounted on a shaft R, turning in bearings r r, Fig. 3. Mounted on the other end of this shaft in a direction substantially at right angles to the arm l is an arm s, the position of the arms being such that as the arm l is moved back and forth the arm s will be raised or lowered. To the arm s is connected a rod t t', the other end of which is attached to the switch-tongue T. As will be understood from the drawings, as the rocking rod L is moved back and forth by the arm K it turns the shaft R and by means of the arm s and rod t t' slides the switch-tongue in an open or closed position.

It will be evident, as far as the operation of the switch mechanism is concerned, that the actuator A in the rail may be lifted by any suitable mechanism, it being only necessary to raise the movable end a of the actuator in position to be depressed by the car-wheel. When used in connection with what are termed "electric" roads—that is, roads in which the cars are propelled by electric motors—the actuator may be raised by an electromagnet. The magnet is placed on the under side of the car in front of the wheel, as shown at V, Fig. 4, and when it is desired to operate the switch mechanism to reverse the switch the electric fluid is turned on the magnet as the car approaches the actuator, and when over the latter the magnet will attract and lift up the end of the actuator, and thus raise the post and set the mechanism ready to be operated by the depression of the actuator by the car-wheel.

On the actuator is a counterpoise-weight W, which serves to balance the weight of the post B and facilitate the movement of the actuator.

In the particular construction shown in the drawings the switch-operating mechanism is in duplicate—that is, there are two posts B with their connecting-arms E and F on each side of the pit, operated by actuators in each of the rails, whereby the wheels on each side of the car move the switch. In this construction, as will be seen, the shaft C, on which the arms E and K are mounted, extends across the pit, and the two sets of mechanism are thereby made to move simultaneously in op-

erating the switch. For all practical purposes, however, this duplicate system is not required, a single set of mechanism operated by an actuator in one of the rails being sufficient to move the switch.

The method of operating or reversing the switch by this mechanism is as follows: As the motorman or driver on the car approaches the switch he observes whether it is turned in the proper direction, and if it is pays no attention to the switch mechanism, but allows his car to run over the rails in the direction desired. If, however, he observes that the switch is not turned in the proper direction—that is, if it is open and he desires it closed or closed and he requires it open—before his car reaches the actuator A in the rail he turns the electricity into the magnet V, and as the front end of the car on which the magnet is placed passes over the actuator the magnet attracts and lifts up the latter in front of the car-wheel, and as the car passes along the wheel depresses the actuator, thus operating the mechanism and reversing the switch, whereby the latter is set in the proper direction before the car reaches it. It will be observed that the only action on the part of the motorman when the switch is to be reversed is to turn the electricity into the magnet, and the car as it passes along itself operates the mechanism and turns the switch, and that it is not necessary to stop the car or interfere in the least with its progress.

What I claim is—

1. In a railroad-switch, in combination, an actuator located in the car-track and adapted to be raised by mechanism on the car, and afterward depressed by the car-wheel, a magnet on the car by which the actuator is raised, and mechanism connected with the actuator and with the switch and operated by the former, whereby when the actuator is depressed the switch is reversed, substantially as described.

2. In a railroad-switch, in combination, an actuator located in the car-track and capable of being raised by mechanism on the car and afterward depressed by the car-wheel, a vertically-sliding post B attached to and operated by the actuator, oscillating arms E and F arranged and adapted to engage alternately with the post, and mechanism connecting the arms with the switch, whereby as the post moves down it engages with either one of the arms and reverses the switch, substantially as described.

3. In a railroad-switch, in combination, the actuator A located in the car-track and capable of being raised by mechanism on the car and afterward depressed, by the car-wheel; vertically-sliding post B, arms E, F connected together and adapted to engage alternately with the post, means whereby the disengaged arm is held from engagement with the post; mechanism connecting the arms with the switch, whereby as the post moves down it

engages with either one of the arms and reverses the switch; and a magnet located on the car by which the actuator is raised, substantially as described.

5. 4. In a railroad-switch, in combination, the actuator A, located in the car-track; post B attached to and operated by the actuator; arms E and F connected together and mounted on shafts C and D and adapted to engage alternately with the post; means whereby the

disengaged arm is held from engagement with the post; arm K mounted on and moving with the shaft C; mechanism connecting the arm K with switch; and the magnet V on the car and adapted to raise the actuator, substantially as described. 15
